UNITED STATES PATENT OFFICE

CHARLES W. PETERSON, OF ANN ARBOR, MICHIGAN

CONICAL-DIAPHRAGM SOUND REPRODUCER

Application filed December 10, 1924. Serial No. 755,056.

My invention relates to devices for reproducing sound under impelled oscillations, such as imparted by the armature of an electro-magnetic receiver in radio receiving sets.

5 It has as its object a simple structure, which can be manufactured in quantities at low cost.

The principal object, however, is to provide for a conical diaphragm of inexpensive 10 material, such as parchment paper, which is supported in such a way as to possess to a minimum degree those overtones, and false lines of strain, which distort the reproduction of the true oscillations imparted to it.

15 My object is to support the cone so that the entire device is free to move, and the rim is lightly engaged by material which serves merely to hold the cone in shape and permit it to move in a resilient manner, and to absorb 20 such oscillations or prevent the formation of oscillations which cause fluttering of the cone edge.

I accomplish my objects by that certain construction and arrangement of parts to 25 be hereinafter more specifically pointed out and claimed.

In the drawings:

Figure 1 is a front elevation of the device.

Figure 2 is a central vertical section there- 30 of on the line 2—2 of Figure 1.

Figure 3 is a detail section of a modified device.

Figures 4 to 6 inclusive are further details 35 of modified ways of providing for a freely vibrating peripheral support for the conical diaphragm.

In providing a framework for my device I have endeavored to simplify it as much as possible.

40 I provide a metal casting having a base 1, with a ring extending upwardly from the base, as at 2. Also extending up from the base in front of the ring is a standard 3, which divides into two arms 4, 4, and which 45 arms have secured across between them a supporting plate 5 for a receiver or transmitter having a vibrating armature.

In the preferred form the diaphragm is 50 formed of parchment paper, in a cone 7, at the apex of which is mounted by means of a

pair of small metal cone pieces 8, a socket 9. The vibrating wire 10 from the armature is held in this socket piece 9, as by a set screw. This links the center of the diaphragm to the armature.

55 The cone is held in place so as to vibrate without false lines of strain or distortion and without undesired overtones by gripping it over the wire 10, by means of the set screw, as shown, and as a preferred, edge or peripheral protection the ring 2 is formed with a hollow, front face, and the clamping ring 12 is bolted to it so as to hold a channel piece 13, of felt or the like. The unbroken periphery of the diaphragm is set into light 60 contact with the felt channel so as to merely rest in place, without any metal contact.

65 In Figure 3 the ring 20 taking the place of ring 2 is illustrated as having a half circle form, with the cavity facing inward. This 70 cavity is filled with a resilient aperiodic material 20^a, such as dry cotton or spongy rubber, and the diaphragm 21, in the form of a cone is merely set in place by permitting its periphery to slightly touch against the 75 exposed face of the resilient filling. The use of felt is preferred because of its characteristic aperiodic nature and the action of the fibres thereof in preventing fluttering to develop in the cone.

80 In Figure 4 the ring corresponding to ring 2 is shown at 50, having a concave cross section, terminating in an upward flange 51. The clamping ring 52 has a like conformation. A pair of rings 53 of rubber or some 85 other flexible or resilient medium, are set over the unbroken edge of the diaphragm 54, and held in place by screwing the two flanges of the rings together over the rings of rubber 53.

85 In Figure 5 the ring 70 faced, for neatness, with a ring 71, as in the last instance, is provided with a ring 72 of cotton wool or the like, cemented to its rearward face.

90 The diaphragm 73 having unbroken 95 periphery, is pulled with its edge against the cotton wool facing to the back of the ring 70, by means of the connector 74 with the armature. The edge in this instance is free to vibrate slightly, and to slide slightly, as a 100

result of impressed oscillations at its center.

In Figure 6 the opposite relation is shown in which the ring 80 is a plain ring, and the attached ring 81 has the felt or other resilient material facing 82. In this case the connection 83 with the armature is adjusted to push the center of the cone 84 away from the armature, thereby holding it against the felt facing on its outer, unbroken edge.

10 It is evident that the various forms illustrated are merely a series of ways of accomplishing my main object, and that other ways could be devised which would likewise meet my purpose. I do not insist on the diaphragm being composed of the precise substance described as other non-metallic or resilient metallic substances would serve.

Having thus described my invention, what I claim as new and desire to secure by Letters Patent, is:—

15 1. In a loud speaker having a receiver with a diaphragm connection, a cone of light, vibrant material exposed to unconfined air, mounted at its apex on the diaphragm connection and an aperiodic substance engaging the periphery of the cone and having sufficient mass to prevent oscillations at the rim of the cone other than those oscillations due to sound generating movement of the cone 20 imparted by the receiver.

2. In a sound reproducer, the combination with a receiver having a diaphragm connection, of a light, vibrant cone secured to said diaphragm connection, a frame and support therefor, and a body of resilient felt deadening material held on said frame, said cone being so mounted on the diaphragm connection as to touch lightly against the deadening material, forming an aperiodic engaging means for the periphery of the cone, without interfering with sound generating movements of the cone imparted by the receiver.

3. In a sound reproducer, the combination with a receiver having a diaphragm connection, of a light, vibrant cone secured to said diaphragm connection, a frame and support therefor, and a body of resilient felt deadening material held on said frame, said cone being so mounted on the diaphragm connection as to rest lightly against the deadening material, forming an aperiodic engaging means for the periphery of the cone, without interfering with movements of the cone as a whole with low period vibrations, said frame 50 being formed as a ring on the support, and a facing ring to conceal the seat of the cone detachably secured to the ring and lying out of contact with the cone.

4. In a loud speaker the combination with a receiver having a diaphragm connection, of a light vibrant cone supported at its apex on the diaphragm connection, and aperiodic means about the entire rim of the cone preventing rim distortions and hence fluttering 55 without interfering with movements of the

cone as a whole, and without imparting internal strains to the cone by a stretching thereof, said cone being freely exposed to unconfined air.

5. In a cone type speaker, a frame having parallel annular supporting members, a tympanum movably disposed intermediate said annular members.

6. In a cone type speaker, parallel annular members, and a tympanum slidably seated 75 between said annular members.

7. In a loud speaker, a conical diaphragm supported in free access to air, a driving motor, a frame and connections arranged to hold the driving motor and diaphragm in proper relation and having a rim projecting beyond the edge of the diaphragm, and an aperiodic material disposed between the edge of the diaphragm and the rim and in contact with both.

8. In a loud speaker, a conical diaphragm supported in free access to air, a driving motor, a frame and connections arranged to hold the driving motor and diaphragm in proper relation and having a rim projecting 80 beyond the edge of the diaphragm, and an aperiodic material disposed between the edge of the diaphragm and the rim and in contact with both, said aperiodic material being soft 85 and flexible enough to allow free sound generative motion of the diaphragm at the edge.

9. In a loud speaker, a conical diaphragm supported in free access to air, a driving motor, a frame and connections arranged to hold the driving motor and diaphragm in proper relation and having a rim projecting 90 beyond the edge of the diaphragm, and an aperiodic material disposed between the edge of the diaphragm and the rim and in contact with both said aperiodic material being soft 95 and flexible enough to allow free sound generative motion of the diaphragm edge, and yet having sufficient damping action to prevent fluttering of the edge of the diaphragm.
